CARVER

Alfred E. Walters, Seattle, Wash.

Application January 7, 1949, Serial No. 69,777

1 Claim. (Cl. 30—296)

1
My invention relates to carvers and more particularly to carving utensils such as carving knives and forks used primarily in carving articles of food.

It is a primary object of my invention to provide a carver wherein the handle is disposed angularly downwardly and outwardly from the plane of the blade of the carver.

It is a further object of my invention to provide a carver and particularly a carving knife which may be disposed on a supporting surface such as a work table and where the handle will function as a support or rest for the knife and the blade of the knife will be disposed in a plane substantially at 45° to the supporting surface. This provides, not only for protection of the cutting edge of the knife, but further provides for safety as the cutting edge of the knife is angularly directed downwardly.

It is a further object of my invention to provide a carver wherein the cutting pressure of the operator is reflected over the entire hand of the operator rather than merely being fulcrumed about the operator's thumb as is common in conventional carvers.

It is a further object of my invention to provide a knife so shaped and arranged that the forearm, wrist, and hand of the operator are in a natural and normal position rather than in a twisted position. This is to be distinguished from the mode of operation of conventional knives and thus carvers of my invention minimize strain on the operator's wrist, provide for more ease of operation, and for more accuracy in cutting. Obviously, where a knife is being guided and there is less strain on the wrist of the operator, there is less likelihood of accidental cutting of the operator.

It is a further object of my invention to provide carvers of a construction which permit balance in the carver and not only aid the operator in the carving operation, but permit maximum ease and comfort to the operator during the carving operation.

The above mentioned general objects of my invention, together with others inherent in the same, are attained by the devices illustrated in the accompanying drawings throughout which like reference numerals indicate like parts.

Figure 1 is a view in side elevation of one form of knife embodying my invention, and with the knife blade disposed in a vertical plane;

Fig. 2 is an end elevation of the construction shown in Fig. 1;

Fig. 3 is a plan view thereof;

2
Fig. 4 is a sectional view taken substantially on broken line 4—4 of Fig. 3;

Fig. 5 is a sectional view taken substantially on broken line 5—5 of Fig. 3;

Fig. 6 is a view in side elevation indicating the manner in which the tools of Figs. 1 to 5 of the drawings may be laid on a support or rest; and Fig. 7 is an end view thereof.

Referring now to the construction shown in Figs. 1 to 7 of the drawings, a carver tool, such as blade 18, is provided and the same may have any desirable shape. However, the contour of the cutting edge 19 is preferably provided as will be hereinafter explained. A handle member 20 preferably is formed of any suitable transparent or translucent plastic material for decorative effects. The handle member 20 is disposed with its longitudinal axis angular in two directions to the plane of the blade 18. If the blade 18 is disposed in a vertical plane, with the longitudinal axis thereof in a horizontal plane and with the cutting edge 19 downwardly, as indicated in Figs. 1 to 5 of the drawings, the longitudinal axis of the handle member 20 angles downwardly from the blade 18 to form an obtuse angle of substantially 135°, as is indicated in Fig. 1 of the drawings, and also angles laterally therefrom to form an obtuse angle of substantially 135°, as is best shown in Fig. 3 of the drawings. The upper surface 21 of the handle member 20, as viewed in Figs. 4 and 5 of the drawings, is convex in transverse section while the lower surface 22, of the handle member 20, is concave in transverse section. The handle member 20 is somewhat pear shaped in plan and tapers toward the outer end portion 23, as is best shown in Fig. 3 of the drawings. The knife blade 18 is formed of any suitable steel and the heel portion 24 thereof is embedded in the handle 20. The heel portion 24 may, if desired, come to the surface of the plastic handle and be ground to the contour thereof as is indicated in Figs. 1 and 2 of the drawings. Preferably an opening 25 is provided in the heel portion 24 and which is filled with plastic to provide for a more secure union between the heel portion 24 of the blade 18 and the handle member 20. Also the portion 26 is dull to function as a rest in the event it is desired to rest the knife, when not in use, on a supporting surface as is indicated in Figs. 6 and 7 of the drawings. In such figures, the knife and handle member may be supported and have a three point suspension, wherein the knife portion 26, the heel or butt portion 28, and the toe or outer end portion 23 rest on the supporting surface 27.

When the knife is at rest, it may be placed in the positions shown in Figs. 6 and 7 of the drawings but, when the knife is in use, the blade 18 will generally not be angularly disposed to the vertical and will generally be in a vertical plane as is indicated in Figs. 1 to 5 of the drawings. In cutting with the knife, shown in Figs. 1 to 7 of the drawings, the knife will generally be pushed or pulled away from or toward the user and, during movement, the pointed end of the blade 18 will be pointed downwardly and at an angle of about 45° to the horizontal. This puts the pressure of the operator's fist behind the cutting pressure during pushing of the knife.

Also during use of the knife and if a substantially vertical cut is being made of articles such as meat, the handle member 20 will extend downwardly and rearwardly and the forearm, wrist, and hand of the operator are in a natural, rather than in a twisted, position. Also the handle member 20 should be of a size to conveniently fill the hand of the operator and thus the operator's full hand is being employed and we do not have a grasp of the handle wherein the operator employs his thumb as a fulcrum and tends to lift up with the outer end of the handle in order to force the pointed end of the blade downwardly. The operator's fingers pass about the handle member 20 and the first four fingers will be received in the concave portion 22 while the thumb may extend about the rounded portion at the heel or butt portion 28 of the handle member 20.

The knife of Figs. 1 to 7 of the drawings is a knife for a right handed operator. Obviously to make a knife for a left handed operator, the parts can be appropriately changed to provide mated parts.

In the figures illustrating my invention, I have provided knives which are generally characterized in that the operator closes his hand about the knife and fills his hand so that the cutting action obtains by the use of the entire pressure of the hand rather than by attempting to lift up the fingers and push down on the thumb as obtains with the use of ordinary knives. Also in the various embodiments of my invention, the lon-

itudinal axis of the handle is angled downwardly and outwardly from the longitudinal axis of the carving utensil as distinguished from being generally aligned therewith in accordance with common practice. While such angles change with various embodiments of my invention, for a particular knife or carving utensil, the angles may be adjusted to obtain desired balance so that the knife permits the operator to employ natural and unstrained positions of his forearm, wrist, and hand during carving.

Obviously changes may be made in the dimensions, arrangements and forms of my invention without departing from the principle thereof, the above setting forth only preferred forms of embodiment.

I claim:

20 A dinner knife comprising a handle, said handle including an enlarged heel surface contacting portion and a tip surface contacting portion for normally supporting the knife on a horizontal surface, a knife blade rigidly connected to the handle at the heel thereof, the said blade extending laterally of the handle when said handle is supported on a surface, the plane of said blade being disposed at an obtuse angle to the axis of the handle and at an acute angle to a plane through the surface contacting portion of the heel and tip.

30 ALFRED E. WALTERS.
